UNITED STATES PATENT OFFICE.

STACY B. HASELTINE, OF CHICAGO, ILLINOIS, ASSIGNOR TO W. H. MINER, INC., OF CHICAGO, ILLINOIS, A CORPORATION OF DELAWARE.

SHOCK-ABSORBING MECHANISM.

Application filed February 28, 1927. Serial No. 171,416.

This invention relates to improvements in shock absorbing mechanisms. One object of the invention is to provide a shock absorbing mechanism of the tandem spring type, especially adapted for railway draft riggings, including front and rear main followers and intermediate followers co-operating with the springs, wherein the intermediate followers are both provided with means co-operating with both main followers when the mechanism is fully compressed to limit approach of the same and provide column load transmitting means of exceptional strength to prevent undue compression of the main spring resistance elements.

Another object of the invention is to provide a spring shock absorbing mechanism of the character indicated, including front and rear main followers, and front and rear intermediate followers co-operating with tandem springs and each having arms in the form of continuous bars extending forwardly and rearwardly therefrom, wherein the continuous bars function as a column load transmitting means when the mechanism is fully compressed to transmit the force direct from one main follower to the other and prevent the springs from being compressed to an excessive degree.

A more specific object of the invention is to provide a tandem spring shock absorbing mechanism including front and rear main followers, pressure transmitting bars interposed between the main followers, certain of which bear on the front main follower and have their rear ends spaced from the rear main follower and others of which bear on the rear main follower and have their front ends spaced from the front main follower, the spacing of said bars from the respective main followers being equal to the predetermined compression stroke of the mechanism, whereby when the mechanism is fully compressed, the bars will act as a stop column means to limit the approach of the main followers; a front intermediate follower fixed with respect to the bars bearing on the rear main follower, a rear intermediate follower fixed with respect to the bars bearing on the front main follower, and tandem arranged springs, one member of which is interposed between the front main and the front intermediate followers and the

other of which is interposed between the rear intermediate and rear main followers.

Other objects and advantages of the invention will more fully and clearly appear from the descriptions and claims hereinafter following:

In the drawings, forming a part of this specification, Figure 1 is a horizontal, longitudinal, sectional view of a portion of a railway draft rigging, showing my improvements in connection therewith. Figure 2 is a vertical transverse sectional view corresponding substantially to the line 2—2 of Figure 1 the springs being omitted. Figure 3 is a plan view of one of the combined pressure transmitting and intermediate follower members of my improved spring shock absorbing mechanisms. And Figure 4 is a front end elevational view of the member illustrated in Figure 3.

In said drawings, 10—10 indicate channel-shaped center or draft sills of a railway car underframe, to the inner sides of which are secured the usual front stop lugs 11—11 and rear stop lugs 12—12. The inner end portion of the drawbar is indicated by 13, to which is operatively connected a yoke 14 of well known form. My improved shock absorbing mechanism proper and the front and rear main followers 15 and 16 are disposed within the yoke, and the yoke in turn is supported in operative position by a detachable saddle plate 17 fixed to the draft sills.

The improved shock absorbing mechanism co-operates with the front and rear main followers 15 and 16 and comprises broadly: A combined pressure transmitting member and front intermediate follower A; a combined pressure transmitting member and rear intermediate follower B; and tandem arranged spring resistance elements C—C.

The front and rear combined pressure transmitting member and intermediate followers are of similar design, but reversely arranged. Each of these combined members comprises a transverse intermediate follower member 18 having forwardly and rearwardly projecting arms at two diagonally opposite corners thereof. The forwardly projecting arms of the front member A are designated by 19 and the rearwardly projecting arms thereof are designated by 20. As most clearly shown in Figure 3, the arms

19 and 20 on each side of the follower 18 are in longitudinal alignment and in effect form a continuous bar member. As clearly shown in Figures 1 and 3, the arms 19 are 5 longer than the arms 20. Each of the arms 19 and 20 are of angular cross section as most clearly shown in Figures 2 and 4. The combined pressure transmitting member and followers A and B are reversely ar- 10 ranged with the forwardly projecting arms of the member A embracing the intermediate follower section 18 of the member B, the section 18 being cut away at diagonally opposite sides as shown in Figure 4 to ac- 15 commodate these arms. The rearwardly projecting arms of the member B which are also designated by 19, embrace the follower element 18 of the member A, the follower element 18 being cut away at opposite sides 20 similar to the member 18 hereinbefore de- scribed, to provide clearance for these arms. The forwardly projecting arms of the mem- 25 ber B are also designated by 20 and are shorter than the arms 19 thereof. The lon- gitudinal meeting edges of the arms 19 and 20 of the members A and B are provided with horizontal flanges 21 providing flat bearing surfaces for these arms.

As clearly shown in Figure 1, the arms 30 19 of the member A bear on the front main follower 15 and the rear ends of the arms 20 of this member are spaced from the rear follower 16 a distance equal to the permissible compression stroke of the mechanism, 35 and the arms 19 of the member B bear on the rear main follower 16 and the front ends of the arms 20 of this member are spaced from the main follower 15 a distance equal to the spacing between the rear ends of 40 the arms 20 of the member A and the follower 16. It will thus be evident that when the mechanism is fully compressed, the opposite ends of the bar-like members comprising the arms 19 and 20 of the two members 45 A and B will be engaged simultaneously by the front and rear followers 15 and 16, thereby positively limiting the compression of the mechanism, the bar elements acting as column load transmitting stop members to prevent the springs from being unduly compressed. The intermediate follower 18 of the member A functions as a rear intermediate follower and bears on the front end of the rear spring resistance C and the intermediate follower member 18 of the member B functions as a front intermediate follower and bears on the rear end of the front spring resistance C.

The tandem arranged spring resistance 60 elements C comprise two members, each including a light inner coil and a relatively heavier outer coil. The coils of the front spring resistance element are interposed between the front main follower 15 and the front intermediate follower 18, and the coils

of the rear spring resistance element are interposed between the rear intermediate follower 18 and the rear main follower 16.

The operation of my improved shock absorbing mechanism, assuming a compression 70 stroke, is as follows: The main followers 15 and 16 will be moved relatively toward each other, thereby forcing the rear intermediate follower toward the rear main follower and the front intermediate follower toward the 75 front main follower through the medium of the arms 19 and effecting compression of the main spring resistance means in tandem. Compression of the mechanism will continue either until the actuating force is reduced, 80 or the outer ends of the arms 20 come into engagement with the front and rear main followers 15 and 16, whereupon relative movement of the main followers will be positively stopped, the bar members comprising 85 the arms 19 and 20 acting as column load transmitting means directly transmitting the force from one follower to another, thereby preventing undue compression of the main springs. Upon release, when the 90 actuating force is reduced, expansion of the spring resistance means C will return all of the parts to the normal position shown in Figure 1.

While I have herein shown and described 95 what I now consider the preferred manner of carrying out my invention, the same is merely illustrative, and I contemplate all changes and modifications that come within the scope of the claims appended hereto. 100

I claim:

1. In a shock absorbing mechanism, the combination with front and rear main followers; of front and rear intermediate followers, said rear intermediate followers 105 being provided with forwardly projecting and rearwardly projecting arms, said forwardly projecting arms bearing on the front main follower and said rearwardly projecting arms being normally spaced from the rear main follower and adapted to engage said rear follower when the mechanism is fully compressed, said front intermediate follower also being provided with forwardly and rearwardly projecting arms, said last 110 named forwardly projecting arms being normally spaced from the front main follower and adapted to engage the same upon full compression of the mechanism and said last named rearwardly projecting arms 120 bearing on the rear main follower; and front and rear springs interposed respectively between said front main and front intermediate followers and said rear main and rear intermediate followers. 125

2. In a tandem spring shock absorbing mechanism, the combination with front and rear main followers; of two sets of pressure transmitting bars interposed between said main followers, said bars all being of uni- 130

- form length, one set of bars bearing on the front main follower and movable therewith and having their rear ends spaced from the rear main follower and the other set of bars bearing on the rear main follower and being movable therewith and having their front ends spaced from the front main follower a distance equal to the spacing between the rear main follower and the rear ends of said first named set of bars, all of said bars engaging both of said main followers upon full compression of the mechanism; front and rear intermediate followers movable respectively with said sets of bars movable with the rear and front main followers; and tandem arranged springs, one member of which is interposed between the front main and front intermediate followers and the other of which is interposed between the rear main and rear intermediate followers.
3. In a tandem spring shock absorbing mechanism, the combination with front and rear main followers; of front and rear intermediate followers, each having on two diagonally opposite sides thereof continuous bar-like arms projecting forwardly and rearwardly therefrom, said intermediate followers each being cut away at the remaining two diagonally opposite sides, said rear intermediate follower being arranged with the forwardly projecting arms thereof working in the cut away portions of the front intermediate follower and bearing on the front main follower, and the front intermediate follower having the rearwardly projecting arms thereof working in the cut away portions of said rear intermediate follower and bearing on said rear main follower; a spring resistance element interposed between said front main and front intermediate followers; and a spring resistance element interposed between said rear main and rear intermediate followers.
4. In a tandem spring shock absorbing mechanism, the combination with front and rear main followers; of front and rear intermediate followers, each having on two diagonally opposite sides thereof continuous angular bar-like arms projecting forwardly and rearwardly therefrom, said rear intermediate follower being arranged with the forwardly projecting arms thereof bearing on the front main follower, and the front intermediate follower having the rearwardly projecting arms thereof bearing on said rear main follower; a spring resistance element interposed between said front main and front intermediate followers, and a spring resistance element interposed between the front main and rear intermediate followers, each of said intermediate followers being movable toward and away from each other; of front and rear intermediate followers, each of said intermediate followers being provided with longitudinally disposed side arms, forwardly and rearwardly projecting therefrom, one front and one rear arm of each intermediate follower being continuous and disposed in alignment and forming in effect a continuous bar member, the front arms of the rear intermediate follower being longer than the rear arms thereof and bearing on the front main follower, and the rear arms of the front intermediate follower being longer than the front arms thereof and bearing on the rear main follower, said continuous bar members of the front and rear intermediate followers being of uniform length; and tandem arranged springs, one member of which is interposed between the front main and front intermediate followers and the other member of which is interposed between the rear main and rear intermediate followers.
5. In a tandem spring shock absorbing mechanism, the combination with front and rear main followers; of a plurality of pressure transmitting bars interposed between said main followers, said pressure transmitting bars being of uniform length, said bars being arranged in two sets, one set of bars bearing on the front main follower and movable therewith and having the rear ends spaced from the rear main follower and the other set of bars bearing on the rear main follower and being movable therewith and having their front ends spaced from the front main follower; a rear intermediate follower fixed with respect to said first set of bars and movable therewith; a front intermediate follower fixed with respect to the second named set of bars and movable therewith, and tandem arranged springs, one member of which is interposed between the front main and front intermediate followers, and the other member of which is interposed between said rear main and rear intermediate followers.

In witness that I claim the foregoing I have hereunto subscribed my name this 16th day of February 1927.
